UNITED STATES PATENT OFFICE.

ADEL Y. DODGE AND EUGENE G. McDONALD, OF SOUTH BEND, INDIANA, ASSIGNEES
TO BENDIX BRAKE COMPANY, OF CHICAGO, ILLINOIS, A CORPORATION OF ILLINOIS.

BRAKE.

Application filed January 8, 1926. Serial No. 79,946.

This invention relates to brakes, and is illustrated as embodied in an internal expanding three-shoe "Bendix" brake. An object of the invention is to provide positive but inexpensive positioning means for the shoes, or equivalent friction means, and for a floating self-centering brake-applying device.

In one desirable arrangement, interengaging positioning devices are provided on the shoes or the like and on an adjacent support, having for example a flange-and-groove connection with each other, to position the shoes laterally. We prefer that 10 one or both of these parts have an additional function, so that they add nothing to the cost of the brake. Thus one device may be a stop, preferably an adjustable eccentric, and the other may be the pivot or other 15 joint member connecting the shoes. This latter arrangement involves, as an additional feature of novelty the use of the joint member as the part engaging the stop to position the shoes when the brake is not 20 applied, whether or not it interlocks with the stop as just described.

Another important feature of novelty relates to providing a stop, preferably a novel 25 pressed metal eccentric, for a floating bracket or other support carrying the outer end of the brake-applying shaft, thus limiting movement of the support to insure 30 against dragging of the shoes.

The above and other objects and features 35 of the invention, including various novel combinations of parts and desirable particular constructions, will be apparent from the following description of one illustrative embodiment shown in the accompanying 40 drawings, in which:

Fig. 1 is a vertical section through the 45 brake, just inside the wheel, showing the shoes in side elevation, and with the end of one shoe broken away;

Fig. 2 is a section on the line 2—2 of Fig. 45 1, showing the joint between the shoes; and

Fig. 3 is a radial section on the line 3—3 of Fig. 1, showing the novel stop which positions the floating bracket.

The particular brake illustrated includes a 50 drum 10 and backing plate 12, between which are arranged a shoe 14 anchored at 16 on the backing plate, a shoe 18 anchored at 20, and a floating or servo shoe 22.

Shoes 14 and 22 are preferably identical and

interchangeable, and are forked at their ends (see Fig. 2) to straddle opposite ends of shoe 18. This arrangement is more fully described in Patent No. 1,622,133, granted Bendix Brake Company on application of 60 A. Y. Dodge.

Shoes 14 and 22 are forced apart to apply the brake, by means such as a double cam 24, against the resistance of a spring 26, and an auxiliary spring 28 insures that 65 shoe 22 will first engage the drum and will then turn slightly with the drum to force shoe 18 against the drum. A spring 30 connected to the backing plate may engage a pin 32 bridging an opening 34 in shoe 22, 70 to urge the shoe laterally toward the backing plate.

Shoes 18 and 22 are shown connected by a 75 novel pivot joint member 36, having near its end an annular groove 38 defining an end flange 40 received in a groove 42 in an adjustable eccentric 44. Groove 42 defines a flange 46 on the eccentric which projects into the groove 38 of the joint member. 80 This positively positions the shoes laterally.

In this particular case, eccentric 44 also serves as an adjustable stop determining the idle position of the shoes, and against which the joint member 36 is urged by spring 28. 85 Flanges 40 and 46 are wide enough so that the flange-and-groove joint between the parts does not separate even when the brake is applied, and there is no interference with brake-applying movement of the shoes.

Stop or eccentric 44 is shown carried by 90 backing plate 12, and as having a head 48 outside the backing plate which can be gripped by a wrench in adjusting the stop. A nut 50 threaded on the stem of the stop serves to clamp it in any desired adjusted 95 position.

Cam 24 or the like is operated by a shaft 52 journaled in a freely-floating support or bracket 54, shown as held laterally by bolts 56 projecting through slots 58 in backing plate 12. In order to prevent shoes 14 and 22, with shaft 52 and support 54, from shifting too far to the left in Fig. 1 (forwardly of the car), thus permitting the shoe 22 to drag, support 54 is engaged by the edge of a 100 novel pressed-metal stop 60, having depressed in its central portion a polygonal socket for the head of a bolt 62, by which it is attached to the backing plate 12. Bolt 62 is slotted in its end, so that it may be 105 110

turned by a screw-driver to adjust the stop, and is clamped in adjusted position by a nut 64.

While not limited to such use, the above arrangement is especially adapted for use with a control of the type shown in Patent No. 1,613,024, granted Bendix Brake Company on application of A. Y. Dodge, and in which a lever fulcrumed on the axle or king pin 10 operates a crank arm on the end of shaft 52, so that when the brake is not applied, the pressure of the lever on the crank arm serves to hold support 54 against stop 60, thus preventing shoe 14 from dragging.

15 While one illustrative embodiment of the invention has been described in detail, it is not our intention to limit its scope to that particular embodiment, or otherwise than by the terms of the appended claims.

20 We claim:

1. A brake comprising, in combination, shoes, a support, a joint member connecting the shoes, and a stop carried by the support and grooved to interengage with one end of 25 the joint member to position the shoes laterally and also when the brake is not applied.

2. A brake comprising, in combination, shoes, a support, a joint member connecting the shoes, a stop carried by the support and 30 grooved to interengage with one end of the joint member to position the shoes laterally and also when the brake is not applied, and a spring urging the joint member toward the stop.

3. A brake comprising, in combination, shoes, a support, a joint member connecting the shoes, and a stop carried by the support and engaging the joint member to position the shoes when the brake is not applied, 40 the joint member and stop having interengaging parts preventing axial movement of the shoes without interfering with brake-applying movement of the shoes.

4. A brake comprising, in combination, 45 shoes, a support, a joint member connecting the shoes, and a stop carried by the support and engaging the joint member to position the shoes when the brake is not applied, the joint member and stop having interfitting 50 groove-and-flange parts preventing axial movement of the shoes without interfering with brake-applying movement of the shoes.

5. A brake comprising, in combination, 55 shoes, a support, a joint member connecting the shoes, and a stop carried by the support and engaging the joint member to position the shoes when the brake is not applied, the stop being formed with a groove and the joint member having a flange projecting into 60 the groove to position the shoes axially without interfering with their brake-applying movement.

6. A brake comprising, in combination, 65 shoes, a support, a joint member connecting the shoes, and a stop carried by the support

and engaging the joint member to position the shoes when the brake is not applied, the joint member being formed with a groove and the stop having a flange projecting into the groove to position the shoes axially without interfering with their brake-applying movement.

7. A brake comprising, in combination, 70 shoes, a support, a joint member connecting the shoes, and an eccentric adjustably carried by the support and interlocked with the joint member to position the shoes when the brake is not applied.

8. A brake comprising, in combination, 75 shoes, a support, a joint member connecting the shoes, and an eccentric adjustably carried by the support and engaging the joint member to position the shoes when the brake is not applied, the joint member and stop having interengaging parts preventing lateral 80 movement of the shoes without interfering with brake-applying movement of the shoes.

9. A brake comprising, in combination, 85 shoes, a backing plate, a pivot joint member connecting the shoes and having an annular groove about the end next the backing plate, and an eccentric shoe-positioning adjustable stop carried by the backing plate and including a flange projecting into the groove.

10. A brake comprising, in combination, 90 shoes, a backing plate, a pivot joint member connecting the shoes and having a flange at the end next the backing plate, and an eccentric shoe-positioning adjustable stop carried by the backing plate and formed 95 with a groove embracing said flange.

11. A brake comprising, in combination, 100 a friction member, a backing plate, a part projecting laterally from the friction member and having an annular groove about the end next the backing plate, and a stop for determining the idle position of said member and having a flange projecting into said groove.

12. A brake comprising, in combination, 105 a friction member, a backing plate, a part projecting laterally from the friction member and having a flange at the end next the backing plate, and a stop for determining the idle position of said member and grooved to embrace said flange.

13. A brake comprising, in combination, 110 a friction member, a backing plate, a part projecting laterally from the friction member and having an annular groove about the end next the backing plate, and an eccentric adjustable stop for determining the idle position of said member carried by the backing plate and having a flange projecting into 115 said groove.

14. A brake comprising, in combination, 120 a friction member, a backing plate, a part projecting laterally from the friction member and having a flange at the end next the backing plate and an eccentric adjustable 125

stop for determining the idle position of said member carried by the backing plate and grooved to embrace said flange.

15. A brake comprising, in combination, 5 shoes, a floating pivot joint member connecting the shoes, and means engaging the pivot joint member and acting through said member to position the shoes axially.

16. A brake comprising, in combination, 10 shoes, a floating pivot joint member connecting the shoes, and a device having an inter-fitting flange-and-groove connection with the pivot joint member and acting through said member to position the shoes laterally.

17. A brake comprising, in combination, 15 a friction device, applying means including a shaft adjacent the ends of said device, a support in which the shaft is journaled and which is mounted to float crosswise of said shaft, and a stop engaging said support to 20 limit its movement in at least one direction.

18. A brake comprising, in combination, 25 a friction device, applying means including

a shaft adjacent the ends of said device, a support in which the shaft is journaled and 25 which is mounted to float crosswise of said shaft, and an adjustable stop engaging said support to limit its movement in at least one direction.

19. An adjustable positioning stop for a 30 floating brake part including a pressed metal eccentric depressed in its central portion to form a polygonal socket for an attaching device.

20. A brake comprising friction means, in 35 combination with three devices spaced approximately equidistant about the brake and all three of which include parts positively holding the friction means against lateral movement, and one of which is operable to 40 apply the brake, and one of which takes the braking torque.

In testimony whereof, we have hereunto signed our names.

ADIEL Y. DODGE.

EUGENE G. McDONALD.
